ERMINIE J. THOMPSON AND JAMES MARKESE, OF CHICAGO, ILLINOIS, ASSIGNEES TO
DELTA STAR ELECTRIC COMPANY, OF CHICAGO, ILLINOIS, A CORPORATION OF
ILLINOIS

VENTILATED SWITCH STUD

Application filed September 18, 1930. Serial No. 482,702.

This invention relates to ventilated switch studs for electric switches which provide a mechanically stronger structure with a lower production cost and permit the operation of the switch with a lower skin effect due to the larger diameter and hollow construction. In making electrical switches where heavy loads of electrical current must be carried therethrough, it is desirous that the structure may be strong and sturdy as well as economical to manufacture. In the past in the manufacture of electrical switches solid rod has been used together with cast parts which have been machined up to the desired shape for providing switch studs for electrical switches and no provision has been made for the ventilation or wherein a better construction could be provided at a lower cost. In our switch structure we accomplish the results desired by providing hard drawn copper tubing instead of solid rods having a ventilating opening through the stud which supports the switch terminal and thus we provide a switch structure wherein a much higher current may be carried at lower temperature rises.

A further advantage of our switch structure resides in the mounting of the terminals on the tubular studs to rigidly support the same thereon, and threading the studs so that clamping nuts and washers may be used to support the studs by the insulators and upon the supporting plate or base for the switch. The switch terminals have complementary ventilating openings which register with the openings of the studs so that a free ventilation of the terminals and base thereof is accomplished in our switch structure. Economy of our construction in the manufacture of electrical switches, together with the higher efficiency in the operation of the switch provides a means of advancement in the art which we believe is of primary importance.

The details of the structure with the particular advantages and further objects will be more clearly defined.

In the drawing forming part of the specification:

Figure 1 is a side view of a switch assem-

bly, showing our ventilating switch studs supporting the switch in operative position.

Figure 2 is a section of one of the ventilating switch studs and terminal.

Figure 3 is a side view of a switch stud and terminal with a ventilating passage.

Figure 4 illustrates another side view of the ventilating stud and terminal.

Figure 5 illustrates a further side view of the ventilating stud and terminal.

Figure 6 is a plan view of Figure 5.

Figure 7 is a plan view of Figure 4.

The switch stud 10 is formed of tubing which may be made of hard drawn copper or other suitable material, having a central ventilating hole 11 through which air may pass to ventilate the stud 10 when it is in operation.

The stud 10 may be threaded on the ends at 12 and 13 and is adapted to support the terminal 14 which is provided with a base portion 15 which may be screwed on to the threaded portion 13, or it may be sweat on to the same, or the base 15 may be attached to the stud in any other suitable manner. The drawing illustrates the base portion 15 threadably secured to the stud 10, and held in this threaded engagement by pins 22 through the base 15 and extending into the stud 10.

The studs 10 may be mounted with insulators such as B to support the switch blades 16 on the supporting plate 17 when it is desired. Any suitable mounting may be employed to support the switch blades 16 so that they will operate with the terminals 14. The studs may be placed as far apart as desired and any mounting may be used.

One or more terminals 14 may be supported from the same base portion 15 as may be desired and even a multiplicity of terminals 14 may be employed with the base structure 15, such as is illustrated in Figures 4 and 7. The base portion 13 may be formed with ventilating openings 18 in the sides of the same which communicate with openings 19 in the studs 10, while the

openings 19 in turn communicate with the center longitudinal ventilating opening 11. Thus permitting the free ventilation of air through the base of the terminal for the 5 switch A. An opening 20 is provided in the base 15 which communicates directly and is in line with the opening 11 so that a direct passage of air may extend freely through the stud 10 and through the base 10 15.

In this manner we provide a switch structure having a free ventilation through the studs 10 and through the base and about the terminals 14. This structure also provides 15 a tubular supporting stud such as 10 upon which the terminals of the switch A are mounted. This tubular form of terminal is mechanically stronger and owing to its large overall diameter a lower skin effect 20 is accomplished in the switch structure for the electrical switch A than in switch construction used heretofore. The accomplishments of our switch have a primary importance in providing a means of producing a switch 25 with a low cost of manufacture and adapted to carry much higher electrical currents with a lower temperature rise, thereby providing greater efficiency in a better and more economical manner. Heavy currents 30 may be easily carried by our switch studs and switch structure. It is a material advantage in electrical switches to provide a construction which will tend to keep down the temperature of the parts in operation.

In accordance with the patent statutes the foregoing description represents the best embodiment of our invention, nevertheless we desire to have it clear that such obvious changes as may be apparent to those skilled 40 in the art should be interpreted within the scope of the following claims.

We claim:

1. A switch structure including, hollow switch studs, terminals supported upon said 45 studs adapted to operate with the switch blades in the operation of the switch, a base on each of said terminals adapted to enclose an end of one of said studs, and ventilating openings between said blades communicating with the hollow opening of said switch studs to provide a free ventilation through said studs and switch terminals.

2. An electrical switch having knife blades, terminals for supporting said blades 55 having bases for mounting said terminals formed therewith, a hollow switch stud for said terminals secured thereto, and an opening in said bases communicating with the hollow opening through said stud.

3. An electrical switch including, knife blades, flat terminal mountings for engagement with said blades, a cap base for said 60 mountings, tubular supporting studs for said terminals, means for securing said base 65 to said tubular supporting studs and air

ventilating openings longitudinally and transversely through said studs and terminals.

4. A ventilated switch stud in combination with a switch blade terminal, including, a hollow stud member, a switch terminal having switch blade engaging surfaces, and ventilating openings formed in said terminal communicating with the ventilating opening extending through said stud. 70

5. A switch stud and terminal for electrical knife blade switches including, a hollow terminal stud, a terminal having a switch blade engaging end, a stud engaging end on said terminal, pin means for attaching said terminal to said stud, and a ventilating opening through said stud engaging end of said terminal adapted to communicate with the hollow switch stud to provide ventilation for said stud and terminal. 75

6. The combination, switch terminals, studs for supporting said terminals, and longitudinal and transverse openings through said studs and terminals to provide ventilation for an electrical switch. 80

7. A ventilated stud for transmitting electrical current including, a hollow stud member, and unobstructed transverse ventilating holes formed therein to permit free passage of air. 85

8. A ventilated stud for transmitting electrical current including, a tubular stud member, an insulating member enclosing said stud member, and transverse ventilating holes formed in the unclosed portion of said air therethrough. 90

9. A ventilated switch stud and terminal including; a hollow tubular switch stud, threads on one end thereof to accommodate a switch terminal, a terminal having switch blade engaging surfaces, a base on said terminal adapted to be threadably secured to said stud, pins for securing said terminal in threadable engagement with said stud, an opening in said base in alignment with the opening through said tubular stud, and a transverse opening through said stud and terminal base communicating with the opening through said tubular stud. 105
